EDGAR M. BENHAM, OF NORWOOD, AND GEORGE J. BAUER, OF MADISONVILLE, OHIO,
ASSIGNORS TO THE MOSLER LOCK COMPANY, OF COVINGTON, KENTUCKY, A COR-
PORATION OF OHIO.

LOCK.

Application filed June 12, 1926. Serial No. 115,443.

This invention relates to locks, and more particularly relates to locks especially suited for safety deposit lock boxes, and to the type which permits the customer's key to be placed in a sealed envelope at the factory and not to be removed therefrom until the key is delivered to the customer.

The principal object of our invention is to improve upon the construction of locks of this character, with the view of obtaining concealment of the serial number of the customer's key until it is desired to deliver this key to the customer. A further object of our invention is to provide a lock of the character described, which gives added protection and security against being unlocked by an authorized person, or by means of unauthorized instruments. A further object of our invention is to provide a simplified lock construction, which does not require the use of the customer's key for partially locking it for shipping or for unlocking and relocking it at will pending renting of the safety deposit lock box to which the lock is applied, but which cannot be unlocked without the customer's key after the serial number of such key has been ascertained. Other objects of our invention will be in part obvious and in part pointed out hereinafter.

In accordance with our invention, we utilize a construction resembling the construction disclosed in patent to Edgar M. Benham, No. 1,522,752, issued January 13, 1925, for locks, and apply to such a construction a special tumbler, on the underside of which is marked the serial number of the customer's key for the particular lock, and provide an aperture in the rear face of the lock case, through which this number is visible, but only when the tumbler has been manipulated into a certain position. Means are provided for preventing this tumbler from so exposing the serial number until the lock has been put in such condition that the customer's key is required to unlock the same. The lock is so constructed that, prior to the exposure of the serial number, the lock may be partially locked and unlocked to permit the door of the box to which the lock is ap-

plied to be secured or opened by means of a temporary guard key and a dummy key. This special tumbler requires the use of a different guard key after the serial number has been exposed, and preferably is designed to prevent the insertion of any master key prior to the exposure of the serial number.

In order that a clearer understanding of our invention may be had, attention is hereby directed to the accompanying drawings, forming a part of this application and illustrating one possible embodiment of our invention.

Referring to the drawings, Fig. 1 is a top elevation of a lock embodying our invention, the bolt bar being shown partially projected; Fig. 2 is a rear view of the same, partially broken away to show the serial number of the customer's key marked on the special tumbler; Fig. 3 is a sectional view of the lock, showing the special tumbler exposed, the bolt bar being partially projected by means of the temporary guard key and the dummy key; Fig. 4 is a view similar to Fig. 3, but shows the bolt bar fully projected of the temporary guard key and the dummy key; Fig. 5 is a side elevation of the temporary guard key; Fig. 6 is a side elevation of the permanent guard key; and Fig. 7 is a side elevation of the dummy key.

Similar reference characters refer to similar parts throughout the several views of the drawings.

As before stated, the lock comprises a suitable casing 1, cover plate 2, slidable bolt bar 3, having a bolt portion 4 and locking stump 5, master key tube 6, with cam 7, for operating the bolt bar, guard key tube 8, and alternately nested guard tumblers 8' and master tumblers 6' commonly pivoted on a post 9, in a manner resembling that disclosed in said Patent No. 1,522,752.

In accordance with the present invention, a special tumbler 10 is pivoted on the post 9 intermediate the bolt bar 3 and the stack of master and guard tumblers. This special tumbler has a tail portion 11, which comes adjacent the guard key tube 8, so that the

tumbler may be pivoted by means of a proper key turned in this key tube. The nose 12 of this special tumbler has two recesses, one of which, 13, is normally in alignment with the locking stump 5, and the other recess 14 being adapted to be aligned with the locking stump 5 only after the locking stump 5 has been withdrawn from the recess 13 and the tumbler pivoted by means of the proper key operating in key tube 8. The back of the case 1 is provided with an aperture 15, and the special tumbler 10 is marked on its under-face with the serial number of the customer's key intended for the lock, as at 16. The aperture 15 is so positioned that in the normal position of the tumbler 10, the serial number thereon is not visible therethrough, and is only visible after this tumbler has been pivoted in the manner above described.

The rear of the lock is provided with another aperture 17, in which is seated normally the head 18 of a screw 19, which is in threaded engagement with the bolt bar. The relative shapes and sizes of the aperture 17 and screw head 18 are such that the bolt is permitted partial reciprocation, just enough to take the locking stump 5 out of engagement with the guard tumblers 8', but not enough to take the locking stump out of engagement with the master tumblers 6', nor out of engagement with the recess 13 of the special tumbler 10. Only after screw 19 has been removed may the bolt bar be fully projected, in which case the special tumbler 10 will be released, but the master tumblers will also have been upset, so as to require the use of the customer's key before the lock may be unlocked.

Preferably, the special tumbler 10 is provided with a portion 20, which, in the normal position of this tumbler, is closely adjacent the front side of key tube 6 and in the path of a key being inserted into this key tube when the lock is in fully locked condition. Thus, when the tumbler is in this position, neither the customer's key, nor any other key, can be inserted to the full extent into this key tube until the tumbler 10 has been pivoted to remove its obstructing portion 20. This requires a special key, operable in key tube 8, for pivoting the tumbler 10 to displace this obstructing portion from the path of a key into the key tube 6. However, unless the bolt bar is fully projected, such key for the tumbler 10 cannot be operated, on account of the engagement of the locking stump 5 in the recess 13 of this tumbler. It will be apparent that when the tumbler 10 is pivoted in the proper manner, the serial number of the customer's key will be visible through the aperture 15 of the lock case, and at the same time the obstruction 20 to the entrance of the custom-

er's key will be displaced, and the recess 65 14 of this tumbler will be aligned with the locking stump 5.

When the lock is shipped from the factory, the screw 19 is in place, and the locking stump is engaged in the recess 13 of the special tumbler 10, and thus the lock is in partially locked condition, as shown in Figs. 1 and 3. The customer's key is preferably placed in a sealed envelope at the factory, and the serial number is marked on the outside of the envelope. Thereafter the custodian of the bank may unlock the lock and restore it to partially locked condition at will by means of a temporary guard key 21, inserted in key tube 8, and a dummy key 22, or other instrument inserted in key tube 6, whereby the key tube 8 may be rotated. The temporary guard key is cut away, as at 24, so as to escape the tail 11 of the special tumbler 10, for otherwise the key could not be turned, due to the engagement of this tumbler with the locking stump 5. This temporary guard key, however, sets up all of the guard tumblers, and since the locking stump holds all the master tumblers in alignment while the screw 19 is in place, the bolt bar may be projected for the distance permitted by the screw 19, and may be retracted by means of dummy key 22. When it is desired to place the lock in condition for operation requiring the use of the customer's key, screw 19 is removed, and the bolt bar is fully projected by means of the dummy key 22. This movement of the bolt bar upsets all the master tumblers, and withdraws the locking stump 5 out of the recess 13 of the special tumbler 10. A permanent guard key 25 is now inserted into the guard key tube 8 and rotated. This permanent guard key has a bit 26, which engages the tail 11 of the special tumbler 10 and causes this tumbler to pivot about the post 9. The serial number of the customer's key is now ascertained by looking through the aperture 15 in the rear of the lock; the sealed envelope marked with the corresponding number is obtained, and the key delivered to the customer. The lock now cannot be unlocked by means of the dummy key, because this key is not capable of setting up the master tumblers. The lock, however, can be locked and unlocked by means of the customer's key, but only after the guard tumblers have been set up and the special tumbler 10 pivoted to remove its portion 20 out of position obstructing the placement of the customer's key fully into the lock. When the customer's key does not enter the lock to the full extent, its bits will not align properly with the master tumblers to set them up.

As many changes could be made in the

above construction and as many apparently widely different embodiments of this invention could be made without departing from the scope thereof, it is intended that all matter contained in the above description or shown in the accompanying drawings shall be interpreted as illustrative and not in a limiting sense.

What we claim is:—

- 10 1. In a lock of the character described, in combination, a casing having an aperture, a bolt bar slidable in the casing, a guard tumbler for dogging the bolt bar, a special tumbler having a key designating mark
15 positioned to be invisible through said aperture in the normal position of the tumbler, said tumbler being movable into position exposing said mark at said aperture, said guard tumbler being movable by means of
20 a key independently of said special tumbler, and said guard tumbler being movable and said special tumbler being disposable into position exposing the mark at the aperture simultaneously by means of another key.

- 25 2. In a lock of the character described, in combination, a casing having an aperture, a bolt bar slidable in the casing, a guard tumbler for dogging the bolt bar, a special tumbler having a key designating mark positioned to be invisible through said aperture in the normal position of the tumbler, said tumbler being movable into position exposing said mark at said aperture, said guard tumbler being movable by means of a key
30 independently of said special tumbler, and said guard tumbler being movable and said special tumbler being disposable into position exposing the mark at the aperture simultaneously by means of another key,
35 and releasable means for locking said special tumbler against movement.

3. In a lock of the character described, in combination, a casing having an aperture, a bolt bar slidable in the casing, a guard tumbler for dogging the bolt bar, a special tumbler having a key designating mark positioned to be invisible through said aperture in the normal position of the tumbler, said tumbler being movable into position exposing said mark at said aperture, said guard tumbler being movable by means of a key independently of said special tumbler, and said guard tumbler being movable and said special tumbler being disposable into position exposing the mark at the aperture simultaneously by means of another key, and releasable means for locking said special tumbler against movement, said means including a projection on the bolt engaging in a recess in the special tumbler.

4. In a lock of the character described, in combination, a casing having an aperture, a bolt bar slidable in the casing, a guard tumbler for dogging the bolt bar, a special

tumbler having a key designating mark positioned to be invisible through said aperture in the normal position of the tumbler, said tumbler being movable into position exposing said mark at said aperture, a recess in said special tumbler, a locking stump on the bolt bar engageable in said recess, and temporary means preventing sufficient projection of the bolt bar to remove the locking stump out of said recess, whereby said mark is retained invisible so long as said temporary means function. 75

5. In a lock of the character described, in combination, a casing having an aperture, a bolt bar slideable in the casing, a guard tumbler for dogging the bolt bar, a special tumbler having a key designating mark positioned to be invisible through said aperture in the normal position of the tumbler, said tumbler being movable into position exposing said mark at said aperture, a recess in said special tumbler, a locking stump on the bolt bar engageable in said recess, and temporary means preventing sufficient projection of the bolt bar to remove the locking stump out of said recess, whereby said mark is retained invisible so long as said temporary means function, said temporary means comprising a removable stop on said bolt bar and having a portion disposed in a slot in the lock casing. 95

6. In a lock of the character described, in combination, a casing having an aperture, a bolt bar slidable in the casing, a guard tumbler for dogging the bolt bar, a special tumbler having a key designating mark positioned to be invisible through said aperture in the normal position of the tumbler, said tumbler being movable into position exposing said mark at said aperture, a recess in said special tumbler, a recess in said guard tumbler, a locking stump on the bolt bar engageable in said recesses, said special tumbler projecting further than the guard tumbler toward the locking stump, and temporary means preventing sufficient projection of the bolt bar to remove the locking stump from the recess of the special tumbler and permitting sufficient projection of the bolt bar to remove the locking stump from the recess of the guard tumbler. 100 105 110 115

7. In a lock of the character described, in combination, a casing having an aperture, a bolt bar slidable in the casing, a guard tumbler for dogging the bolt bar, a special tumbler having a key designating mark positioned to be invisible through said aperture in the normal position of the tumbler, said tumbler being movable into position exposing said mark at said aperture, a recess in said special tumbler, a locking stump on the bolt bar engageable in said recess, and temporary means preventing sufficient projection of the bolt bar to remove the locking 120
125

stump out of said recess, whereby said mark is retained invisible so long as said temporary means function, said temporary means being adjustable to permit sufficient projection of the bolt bar to remove the locking stump out of the recess in the special tumbler.

8. In a lock of the character described, in combination, a casing having an aperture, a bolt bar slidable in the casing, a guard tumbler for dogging the bolt bar, a special tumbler having a key designating mark positioned to be invisible through said aperture in the normal position of the tumbler, said tumbler being movable into position exposing said mark at said aperture, a recess in said special tumbler, a recess in said guard tumbler, a locking stump on the bolt bar engageable in said recesses, said special tumbler projecting further than the guard tumbler toward the locking stump, and temporary means preventing sufficient projection of the bolt bar to remove the locking stump from the recess of the special tumbler and permitting sufficient projection of the bolt bar to remove the locking stump from the recess of the guard tumbler, said temporary means being adjustable to permit sufficient projection of the bolt bar to remove the locking stump out of the recess in the special tumbler.

9. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess.

10. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master

tumbler recess, and temporary means preventing sufficient projection of the bolt bar to remove the stump from the recesses of said tumblers.

11. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess, a key tube from which the master tumbler may be operated, and another key tube from which the special tumbler may be operated.

12. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess, temporary means preventing sufficient projection of the bolt bar to remove the stump from the recesses of said tumblers, a guard tumbler projecting a less distance toward the locking stump than the master and special tumblers and having a recess for the stump, and said temporary means permitting sufficient movement of the bolt bar to remove the stump from the recess of the guard tumbler.

13. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove

- the stump from the special tumbler recess removes the stump also from the master tumbler recess, temporary means preventing sufficient projection of the bolt bar to remove the stump from the recesses of said tumblers, a guard tumbler projecting a less distance toward the locking stump than the master and special tumblers and having a recess for the stump, said temporary means permitting sufficient movement of the bolt bar to remove the stump from the recess of the guard tumbler, and a key for setting up said guard tumbler without engaging said special tumbler.
14. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess, temporary means preventing sufficient projection of the bolt bar to remove the stump from the recesses of said tumblers, a guard tumbler projecting a less distance toward the locking stump than the master and special tumblers and having a recess for the stump, and said temporary means permitting sufficient movement of the bolt bar to remove the stump from the recess of the guard tumbler, said temporary means being removable to permit full projection of the bolt.
15. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess, temporary means preventing sufficient projection of the bolt bar to remove the stump from the recesses of said tumblers, a guard tumbler projecting a less distance toward the locking stump than the master and special tumblers and having a recess for the stump, and said temporary means permitting sufficient movement of the bolt bar to remove the stump from the recess of the guard tumbler, said temporary means being removable to permit full projection of the bolt, a temporary guard key for setting up said guard tumbler without engaging said special tumbler when the bolt bar is only partially projected, and a permanent guard key engaging both the guard and special tumblers for setting them up simultaneously when the bolt bar is fully projected.
16. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess, temporary means preventing sufficient projection of the bolt bar to remove the stump from the recesses of said tumblers, a guard tumbler projecting a less distance toward the locking stump than the master and special tumblers and having a recess for the stump, and said temporary means permitting sufficient movement of the bolt bar to remove the stump from the recess of the guard tumbler, said temporary means being removable to permit full projection of the bolt.
17. In a lock of the character described, in combination, a casing having an aperture, a bolt bar slidable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess, temporary means preventing sufficient projection of the bolt bar to remove the stump from the recesses of said tumblers, a guard tumbler projecting a less distance toward the locking stump than the master and special tumblers and having a recess for the stump, and said temporary

- means permitting sufficient movement of the bolt bar to remove the stump from the recess of the guard tumbler, said temporary means being removable to permit full projection of the bolt, a temporary guard key for setting up said guard tumbler without engaging said special tumbler when the bolt bar is only partially projected, and a permanent guard key engaging both the guard 5 tumblers having a recess, a locking stump on the bolt bar engageable in said recesses, a key tube from which the master tumbler may be operated and having a cam for reciprocating the bolt bar upon rotation of the tube, said special tumbler having a portion positioned in the keyway of said tube obstructing full insertion of a key in said key tube until said special tumbler is actuated to remove said obstructing portion from the keyway. 65
- 10 and special tumblers for setting them up simultaneously when the bolt bar is fully projected, said special tumbler having a second recess positioned to align with the locking stump when said tumbler is set up by means of the permanent guard key. 70
- 15 18. In a lock of the character described, in combination, a casing having an aperture, a bolt bar slideable in the casing, a master tumbler for dogging the bolt bar, a special tumbler having a key designating mark positioned to be invisible through said aperture in the normal position of the tumbler, said tumbler being movable into position exposing said mark at said aperture, each of said 20 tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess, and temporary means preventing sufficient projection of the bolt bar to remove the stump from the recesses of said tumblers, a guard tumbler projecting a less distance toward the locking stump than the master and special tumblers and having a recess for the stump, and said temporary means permitting sufficient movement of the 25 bolt bar to remove the stump from the recess of the guard tumbler, said temporary means being removable to permit full projection of the bolt, whereby said guard tumbler may be set up by means of a temporary 30 guard key independently of said special tumbler when the bolt bar is only partially projected, and both the guard and special tumblers may be set up simultaneously by means of a permanent guard key when the bolt bar is fully projected, and the bolt bar 35 may be reciprocated by means of a dummy key, while the master tumbler is set up, and the master tumbler may be set up and the bolt bar reciprocated by means of a customer's key when the bolt bar is fully projected. 40
- 45 19. In a lock of the character described, in combination, a casing having an aperture, a bolt bar slideable in the casing, a master tumbler for dogging the bolt bar, a special tumbler having a key designating mark positioned to be invisible through said aperture in the normal position of the tumbler, said tumbler being movable into position exposing said mark at said aperture, each of said 50 tumblers having a recess, a locking stump on the bolt bar engageable in said recesses, said tumblers extending the same distance toward the locking stump, whereby any projection of the bolt bar sufficient to remove the stump from the special tumbler recess removes the tumbler, said temporary means being removable to permit full projection of the bolt, whereby said guard tumbler may be set up by means of a temporary guard key independently of said special tumbler when the bolt bar is only partially projected, and both the guard and special tumblers may be set up simultaneously by means of a permanent guard key when the bolt bar is fully projected, said special tumbler having a second recess positioned to 55 60 65 70 75 80 85 90 95 100 105 110 115 120 125
20. In a lock of the character described, in combination, a casing having an aperture, a bolt bar slideable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the stump also from the master tumbler recess, and temporary means preventing sufficient projection of the bolt bar to remove the stump from the recesses of said tumblers, a key tube from which the master tumbler may be operated and having a cam for reciprocating the bolt bar upon rotation of the tube, said special tumbler having a portion positioned in the keyway of said tube obstructing full insertion of a key in said key tube until said special tumbler is actuated to remove said obstructing portion from the keyway. 90
- 25 21. In a lock of the character described, in combination, a casing having an aperture, a bolt bar slideable in the casing, a master tumbler for dogging the bolt bar, a special tumbler having a key designating mark positioned to be invisible through said aperture in the normal position of the tumbler, said tumbler being movable into position exposing said mark at said aperture, each of said tumblers having a recess, a locking stump on the bolt bar engageable in said recesses, said tumblers extending the same distance toward the locking stump, whereby any projection of the bolt bar sufficient to remove the stump from the special tumbler recess removes the tumbler, said temporary means being removable to permit full projection of the bolt, whereby said guard tumbler may be set up by means of a temporary guard key independently of said special tumbler when the bolt bar is only partially projected, and both the guard and special tumblers may be set up simultaneously by means of a permanent guard key when the bolt bar is fully projected, said special tumbler having a second recess positioned to 95 100 105 110 115 120 125

align with the locking stump when said tumbler is set up by means of the permanent guard key, a key tube from which the master tumbler may be operated and having a cam for reciprocating the bolt bar upon rotation of the tube, said special tumbler having a portion positioned in the key-way of said tube obstructing full insertion of the key in said key tube until said special tumbler is actuated to remove said obstructing portion from the key-way. **10**
